UNITED STATES PATENT OFFICE.

WILLIAM RAY WINTERSTEEN, OF DANVILLE, PENNSYLVANIA.

NECK-YOKE ATTACHMENT.

1,093,091.

Specification of Letters Patent.

Patented Apr. 14, 1914.

Application filed January 23, 1914. Serial No. 813,937.

To all whom it may concern:

Be it known that I, WILLIAM RAY WINTERSTEEN, a citizen of the United States, residing at Danville, in the county of Mon-tour and State of Pennsylvania, have invented certain new and useful Improvements in Neck-Yoke Attachments, of which the following is a specification, reference being had to the accompanying drawings.

10 This invention relates to new and useful improvements in neck yoke attachments and the primary object of the invention is to provide a device of this character which may be readily and quickly applied to a neck 15 yoke of any desired size and character and one which may be readily removed, when desired.

A further object of the invention resides in providing a device which is simple and 20 durable in construction, inexpensive to manufacture and one which will be very efficient and useful in operation.

With these and other objects in view, the 25 invention consists in the novel features of construction, combination and arrangement of parts as will be hereinafter referred to and more particularly pointed out in the specification and claims.

In the accompanying drawings forming 30 a part of this application, Figure 1 is a side elevation partly in section of a device constructed in accordance with my invention and showing the same applied to use. Fig. 2 is a front elevation thereof with parts 35 in section. Fig. 3 is a rear elevation of the same, the pole or shaft being disclosed in section. Fig. 4 is a horizontal section through the device. Fig. 5 is a perspective view showing the upper member of the device for engagement with the neck yoke proper; and Fig. 6 is a similar view of the lower member of the device for engagement with a pole.

In describing my invention, I shall refer 45 to the drawing in which similar reference characters designate corresponding parts throughout the several views and in which—

1 indicates a block formed preferably of wood but which may be formed of metal, 50 as found desirable, the side faces of which are flat and the upper face of which is designed convex. The under face thereof is somewhat grooved and engaged with the side faces of this block 55 are the sides of a bent sheet of metal 2, which is designed to form a loop in connec-

tion with the under face of said block, whereby to be applied to a pole 3. The bent sides of the sheet 2 which form the loop, together with the block are secured to the 60 faces of said block by means of the bolts 4 which are threaded into position. The rear edges of the faces of the sheet 2 are cut away or offset somewhat, as shown at 5, to form a shoulder for engagement with the 65 shoulder of the pole, whereby to form an abutment for the device on said pole.

The upper convex face of the block 1 is provided with a notch or groove about centrally thereof, as indicated at 6 and fitted 70 in this notch or groove is the base portion of a clamping loop 7, the latter being adapted for engagement with a neck yoke 8. This clamping loop is formed preferably of thin metal and the base portion thereof 75 has the downwardly projecting wings or ears 9 formed thereon which are bolted to the outer side faces of the sheet or loop 2, by the same means which secures the latter to the block 1. Bolts 10 are adapted to be 80 disposed through the portions of the clamping loop 7, adjacent the free ends thereof, whereby said clamping loop may be adjustably secured to the neck yoke. From this construction, it will be seen that the device 85 may be quickly and readily applied to the pole and neck yoke and readily removed, when desired.

From the foregoing it will be seen that I have provided a simple, inexpensive and efficient means for carrying out the objects of the invention, and while I have particularly described the elements best adapted to perform the functions set forth, it is obvious that various changes in form, proportion 90 and in the minor details of construction 95 may be resorted to without departing from the spirit or sacrificing any of the principles of the invention.

Having thus described this invention, what 100 I claim is:—

1. A neck yoke attachment of the class described comprising a block, a plate bent and arranged against the sides of said block to form a sleeve with respect to the latter for 105 the reception of a pole therethrough, a clamping sleeve having depending spaced ears for engagement with the sides of the block, and means to secure said plate to the ears of said clamping sleeve in position on 110 the block.

2. A neck yoke attachment of the class de-

scribed comprising a block, a plate bent and secured to the sides of said block to form a sleeve with respect to the latter, whereby to receive a pole therethrough, a clamping sleeve having depending spaced apart ears for engagement with the sides of the block, the axis of said clamping sleeve being disposed in a plane at right angles to the axis of the aforesaid sleeve and adapted to receive a neck yoke therethrough, and means to secure the ears of said clamping sleeve in position, said last mentioned means also securing portions of the first mentioned plate in position on the block.

15. 3. A neck yoke attachment comprising a block, a plate bent and arranged against the sides of the said block to form a sleeve with

respect thereto for the reception of a pole therethrough, a clamping sleeve provided with depending ears designed for contact 20 with the sides of the aforesaid plate, the axis of said clamping sleeve being disposed in a plane at right angles to the axis of the first-mentioned sleeve, bolts extending through the block and said plate to secure 25 the latter to said block, one of said bolts also securing the ears of said clamping sleeve to said block, as and for the purpose described.

In testimony whereof I hereunto affix my signature in the presence of two witnesses.

30 WILLIAM RAY WINTERSTEEN.
